UNITED STATES PATENT OFFICE.

HOMER CLYDE SNOOK, OF CYNWYD, AND EDWIN W. KELLY, OF PHILADELPHIA,
PENNSYLVANIA.

VACUUM REGULATION.

1,247,027.

Specification of Letters Patent. Patented Nov. 20, 1917.

Continuation of application Serial No. 848,708, filed July 3, 1914. This application filed June 11, 1915.
Serial No. 33,433.

To all whom it may concern:

Be it known that we, HOMER CLYDE SNOOK and EDWIN W. KELLY, citizens of the United States, of Cynwyd and Philadelphia, 5 State of Pennsylvania, have invented new and useful Improvements in Vacuum Regulations, of which the following is a specification.

Our invention relates to means for regulating the degree of vacuum of an X-ray tube or other vacuum tube.

Our invention resides in means for changing the vacuum of an X-ray tube or other vacuum tube comprising an osmotic member 15 a part of which is thick or massive for purposes hereinafter described; our invention resides in an osmotic regulator for both raising and lowering the vacuum by means of a single osmotic member or membrane; 20 our invention resides in an osmotic regulator in which the regulating gas to be admitted to the vacuum through the osmotic member is liberated or produced as and when required either by electrolysis, dissociation or 25 otherwise; our invention resides also in a regulating system involving the use of an osmotic membrane or osmotic membranes in combination with certain circuit connections and arrangements and auxiliary apparatus. 30 Our invention resides in the structures and apparatus hereinafter claimed.

This application is in part a division and continuation of our application Serial Number 848,708, upon which has been granted 35 Patent No. 1,143,327, June 15, 1915.

For an illustration of some of the forms our invention may take, reference is to be had in the accompanying drawings, in which:

40 Fig. 1 is a longitudinal sectional view through an X-ray tube and its regulators.

Fig. 2 is a horizontal sectional view through the regulators of Fig. 1 with the circuit connections slightly altered.

45 Fig. 3 is a diagrammatic view of circuit arrangements suitable for the practice of our invention.

Fig. 4 is a sectional view through regulators with a diagrammatic illustration of 50 means for heating the osmotic members.

Fig. 5 is a sectional view through a vacuum raising and lowering regulator by which regulating gas may be produced electrolytically.

Fig. 6 is a sectional view through a vacuum raising and lowering regulator in which the regulating gas is produced by dissociation or decomposition of a gas producing material.

Fig. 7 is a fragmentary view illustrating 60 a resistance coil heater for the osmotic member.

Fig. 8 is a diagrammatic view of automatic regulation by use of low tension current.

Fig. 9 is a diagrammatic view of a modified system of automatic regulation by low tension current.

Fig. 9a is a fragmentary view of parts of Fig. 9.

Fig. 10 is a diagrammatic view of automatic regulation in response to high potentials.

Fig. 11 illustrates a modified form of osmotic tube or member suitable for use in 75 connection with a spark gap.

Referring to the drawings, B is the usual bulb of an X-ray tube having the glass anode stem D and the glass cathode stem E. Within the tube are the usual anode or 80 target or anticathode A and the cathode C.

In the example illustrated the head 1, of copper or other suitable material is secured to the metallic tube 2, as of steel, which fits over the tubular glass stem 3 joined to the 85 stem D at 4.

A tube 5, of copper or other suitable material, is set into the head 1 and preferably welded thereto forming a vacuum tight joint. The tube 5 extends through the stem D and at its end is welded or soldered 90

at a vacuum tight joint to the platinum or other tube 6 which is sealed into the end of the glass stem D forming a vacuum tight joint.

A corrugation 6a in the tube 6 yields, under expansion and contraction of the tube 95

5 due to temperature changes, and thereby prevents breakage of seal between tube 6 and glass stem D. Within the tube 5 is disposed a metallic tube 7 which at its inner end has any suitable metallic projection 8 100

forming electrical contact with the tube 5 or head 1. Near its outer end the tube 7 is connected, as by soldering or brazing, to the metallic ferrule 9 embracing the end of the glass stem D. Electrical connection is made 105 from the positive terminal of a suitable high tension source of current with the ferrule 9 or the tube 7. The extreme end of the

tube 7 is connected by rubber hose or otherwise with a supply of any suitable cooling medium, for example a supply of air under pressure, or to a suction pump or partial vacuum.

- 5 Accordingly the air will pass into and through the tube 7, strike the head 1, from which the tube 7 is suitably spaced, extracting heat from the head 1 which conducts the heat away from the target proper, the air then passing outwardly as indicated by the arrow through the annular space between the tubes 5 and 7 to the outer air through perforations 10 in the cap or ferrule 9; or in the reverse direction when tube 7 is connected to a suction pump or partial vacuum.

10 The cathode C is counterbored to receive the tube 11 of copper or other suitable material, there being a vacuum tight joint between the cathode C and the tube 11 as by welding, brazing, soldering, etc. At its other end the tube 11 is welded, soldered or brazed to the platinum tube 12 sealed in the 15 outer end of the glass cathode stem E making vacuum tight joints. Within the tube 11 is a metallic tube 13, spaced at its inner end from the cathode C and having the projection 14 making electrical connection with the cathode C or the tube 11. The other 20 end of the tube 13 is soldered or otherwise connected to the metallic ferrule 14, making an air tight joint therewith, the ferrule 14 being secured upon the end of the outer tube 25 or sleeve 15 of glass or any other suitable material. Electrical connection is made from the negative terminal of the aforementioned source of current with the ferrule 14 or the tube 13 which communicates electrically with the cathode C. The sleeve or tube 15 is supported upon the glass cathode 30 stem E by the member 16, of cork or other suitable material, which has a plurality of longitudinally extending grooves 17 forming air passages.

35 The tube or sleeve 15 preferably terminates in the bell 18 which extends around the bulb B to any suitable distance.

40 Air or other cooling medium is introduced into the tube 13, passes therethrough and strikes the cathode C, cooling the same, and then passes outwardly in the annular space between tubes 11 and 13 into the sleeve or tube 15 thence through the passages 17 45 over the outside of the cathode stem E into the bell 18 from which it issues over the outer surface of the bulb B, all as indicated by the arrows; or in the reverse direction if tube 13 is connected to a suction pump or 50 a partial vacuum. And we have found that the air or other medium issuing from the bell 18 clings or remains close to the bulb B even beyond its middle or equator.

55 Sealed to the bulb B is a tube 19 whose interior space 20 is in communication with

the interior of the bulb B. Supported by the tube 19 is the glass bulb or vessel 21 into which projects the tube 22 of platinum, palladium or any other suitable metal or material which is capable of operation as an 70 osmotic member or membrane. The free end of the tube 22 is closed and its other end is sealed in the glass and its open end communicates with the space 20. A conductor 23 connects at its one end with the tube 22 and 75 at its other end with the platinum or other wire 24 sealed through the wall of the bulb 21. A second platinum or other suitable wire 25 is sealed in the glass wall of the bulb 21 and is connected by conductor 26 80 with the osmotic tube 22.

85 It will be noted that the bulb 21 is completely sealed against the outer atmosphere and is sealed against the interior space 20 communicating with the interior of the X-ray tube B by the osmotic member 22. In the bulb 21 is sealed an isolated charge of regulating gas for admission into the vacuum of the bulb B through the tube 22. The gas so sealed in the bulb 21 may be at atmospheric pressure when the regulator is made, or may be above or below atmospheric pressure, but in any case it is preferably at a pressure high as compared with the pressure within the bulb B. The amount of gas 90 or gases sealed in the bulb 21 is sufficient for a great number of regulations of the vacuum in the bulb B, because of the very great amount of regulating gas in the bulb 21 as compared with the amount in the bulb B 95 at any time.

100 The gas in the bulb 21 is preferably hydrogen, though it is to be understood that any other suitable gas or mixture of gases may be employed. For example, the mono- 105 atomic gases, such as argon, helium, neon, xenon, etc., may be employed either singly or in combination, or in combination with hydrogen or other gas or gases.

110 A second osmotic tube or member 28 is sealed in the glass and has its open end in communication with the space 20, while its outer closed end is within the bulb 29, which is open to the atmosphere at 30, or which may be closed or sealed and contain a gas 115 or mixture of gases in which there is no gas of the character to be transferred from within the bulb B through the tube 28 into the bulb 29 for raising the vacuum, or, more generally speaking, in which the concentration of the gas of the character to be removed from the bulb B is less than it is at any time within the bulb B.

120 A conductor 31 connects at its one end to the osmotic tube 28 and at its other end to 125 the platinum or other wire 32 sealed in the wall of the bulb 29. A conductor 33 connects at its one end to the tube 28 and at its other end to the platinum or other wire 34 sealed through the wall of the bulb 29. 130

When it is desired to lower the vacuum within the bulb B, that is, raise the gas pressure therein, the tube 22 of the lowering regulator is heated by passing an electric current therethrough as from conductors 24 and 23, thence through the tube 22, and thence through conductors 26 and 25. The tube 22 being so heated, hydrogen or other regulating gas will pass by osmosis through bulb 21 through the wall of the tube 22 to the interior of the tube 22, thence to the space 20 and thence into the bulb B, lowering the vacuum, the pressure of the hydrogen or other gas within the bulb B being slight indeed as compared with the pressure within the bulb 21.

If on the other hand it is desired to raise the vacuum of the bulb B, that is, to take hydrogen or other gas out of the bulb B, current is passed through the conductors 32 and 31 thence through the raising regulator tube 28 and thence through conductors 33 and 34 to heat the tube 28, and there being substantially no hydrogen or other gas of the bulb B in the air or within the bulb 29 the hydrogen or other gas will come out of the bulb B by osmotic action through the tube 28 and through its wall into the bulb 29, notwithstanding the fact that the gas pressure in the bulb 29 is very many times higher than the gas pressure within the bulb B.

By preference, particularly when hydrogen is used as the regulating gas, and particularly when the gas within the bulb 21 is entirely or largely hydrogen, we make the osmotic tube 22 of platinum and the osmotic tube 28 of the raising regulator of palladium. That is, in the lowering regulator, under the circumstances described, we prefer to use a material for the tube 22 through which the gas does not so readily pass by osmotic action, while the tube 28 is preferably made of a material through which the gas will very readily pass by osmotic action.

However, in the lowering regulator the osmotic member 22 may be made of palladium or other suitable material which passes through its wall hydrogen or other regulating gas when above a certain concentration and at ordinary temperatures. In such case we prefer to reduce the concentration of the hydrogen or other regulating gas so that when the tube 22 is at ordinary temperature it will not pass hydrogen or other regulating gas. To this end the hydrogen or other regulating gas, whether confined or sealed in the bulb 21 or whether supplied from an external source, is diluted by admixture with some other gas which will not at all or with very great difficulty pass through the osmotic material 22 when at ordinary temperature and when raised to higher temperature by any electrical or other means. Thus, for example, the gas in contact with

or delivered to the outer wall of the tube 22 may be a mixture of substantially ten per cent. hydrogen and ninety per cent. nitrogen, and, the tube 22 being of palladium, for example, little or no hydrogen of such concentration will pass through its wall at ordinary or low temperature, though the reverse is true with higher concentrations. But upon raising the temperature of the material 22, the hydrogen or other regulating gas will pass therethrough into the bulb B to lower the vacuum. By such a combination of material for the tube 22 and diluted gas, a relatively small amount of energy only need be expended upon the material 22 to raise its temperature to a degree to admit regulating gas promptly and in sufficient quantity for vacuum regulation.

Furthermore, the mixture of gases, especially when confined, should be such as to be non-explosive or non-combustible when raised to the temperature to which the tube 22 is raised either by current conducted through the tube 22 as above described, or when using a spark gap to heat the same, as described in our said prior application and in connection with Figs. 5 and 6 herein.

In Fig. 3 G is a source of alternating current, for example, a motor generator or inverted rotary, supplying current through the reversing switch S and adjustable resistance R to the primary p of the transformer T having the high potential secondary s delivering current through the synchronous high potential rectifying switch F to the positive and negative high tension conductors P and N connected respectively to the anode A and cathode C of the X-ray tube. One terminal of the low tension alternating current circuit is connected by conductor 54 with one terminal of each of the transformer primaries p^1 and p^2 whose other terminals connect respectively with one terminal of the resistance r^1 and r^2 adapted to be swept over or engaged by the manually or otherwise operated switch arm 55 connected to the other conductor 56 of the low tension alternating current circuit. Associated with the primaries p^1 and p^2 are the secondaries s^1 and s^2 , in whose respective circuits are included the lowering and raising osmotic tubes 22 and 28. Since these tubes 22 and 28 communicate with the interior of the X-ray tube, during operation of the X-ray tube these regulator tubes assume high potentials, and consequently between the primaries p^1 and p^2 and their secondaries s^1 and s^2 is provided high potential insulation 57.

By this arrangement the X-ray tube may be kept in operation by energy delivered by the high tension conductors P and N and while in operation the vacuum may be lowered by bringing the switch arm 55 into engagement with resistance r^1 , whereupon the secondary s^1 will pass current through the

5 tube 22, the resistance of the tube 22 and the current strength being such that the tube 22 is raised in temperature, the temperature increasing as the amount of resistance r^1 in the circuit is decreased. And similarly if it is desired to raise the vacuum the switch arm 55 is brought into engagement with resistance r^2 whereupon the tube 28 is similarly heated by current derived from the 10 secondary s^2 .

15 A further mode of connecting the osmotic members is shown in Fig. 4, where 35 represents any suitable source of electric energy, as a storage or other battery or generator of direct current, or the secondary of a transformer for delivering alternating current. The source 35 is connected in circuit with the adjustable resistance 36 and the double throw switch 37. When the source 20 35 delivers alternating or fluctuating current the member 36 may be a resistance or a reactance or impedance. When the switch 37 is thrown over to the right it connects with contacts 38 and 39 connected respectively by 25 conductors 40 and 41 with the wires 24 and 25, thus conducting current through the osmotic member 22 to heat the same, the temperature being determined by the current strength which is in turn determined by the 30 adjustable resistance 36. For heating the osmotic member 28 the switch 37 is thrown over to the left in engagement with contacts 42 and 43 communicating, respectively, through conductors 44 and 45 with the conductors 32 35 and 34 to transmit current through the tube 28 whose temperature again is dependent upon a current strength which is again determined by the adjustable resistance 36.

30 Where the osmotic member is heated as above described, it itself operates as a heating resistance to convert the electrical energy into heat whose amount is determined by the square of the current multiplied by the resistance of that part of the osmotic member through which the current flows.

45 In Fig. 5 is shown a regulator comprising a single osmotic member 22^a to be utilized for either raising or lowering the vacuum with which the space 20 is in communication.

50 The tube 22^a consists of palladium, though other suitable material may be employed. In a bell or bulb 29^a, open to the atmosphere at 29^b, is a cork or other member *a* through which extends the glass or other tube *b* in 55 whose outer end is a cork or other stopper member *c* through which extends the wire or conductor *d* terminating in the space *e* between the member *c* and the wall *f* of porcelain or other porous material through which extends the platinum or other conductor *g*, the tube 22^a extending into the mouth of the bottle or tube *b* and separated by a gap from the conductor *g*. The tube 22^a is connected by conductor 23^a to the wire 24^a which may 65 be sealed through the wall of the member

29^a. The wire 25^a may be sealed through the wall of the member 29^a and terminate in a button 26^a separated by a spark gap from the tube 22^a.

70 In the space *e* within the bottle or tube *b* may be placed water, alcohol, oil, such as mineral oil, or any other suitable hydrocarbon or source of hydrogen or other gas required.

75 When it is desired to lower the vacuum of the main bulb or X-ray tube current is passed from the positive conductor *d* through the water or electrolyte in the space *e* to the conductor *g* and thence across the gap to the tube 22^a which is preferably a 80 cathode or negative terminal. The passage of the electric energy through the material in the space *e* causes by electrolysis the evolution of hydrogen, which passes through the porous member *f* into the space surrounding the end of the tube 22^a, and since such tube is heated by passage of the current the gas will pass through the osmotic wall of the tube 22^a into the space 20 communicating with the interior of the main bulb or X-ray 90 tube, to lower the vacuum.

95 Or when oil or other hydrocarbon is in the space *e*, the wires *d* and *g* may be connected together, in which case some of the oil or other material will be carried through member *f* by electrostatic action, and then decomposed into hydrogen or other gas which then passes through the heated wall of the tube 22^a into the main bulb or X-ray tube to lower the vacuum.

100 The same tube 22^a may be used for raising the vacuum, by connecting the wire 25^a with the positive conductor of the circuit and causing the current to leap the gap to the cathode 22^a heating the same, whereupon hydrogen or other gas will pass out of the main bulb or X-ray tube through the wall of the tube 22^a which is surrounded by air, and operation being the same as hereinbefore described.

105 In Fig. 6 there extends through the cork or other stopper a member *h*, of porcelain or other porous substantially non-conducting material. The member *h* may be hollowed out at its inner end as shown to receive the end of the tube 22^a. And the positive conductor *d* may be connected to the member *h* in any suitable way, as by wrapping the same around the member *h* several times. The pores of the member *h* are 110 charged with an oil or hydrocarbon or other suitable material, as described in connection with Fig. 5.

115 On passage of current from the conductor *d* to the tube 22^a which is connected to the negative side of the circuit by wire 24^a gas will be liberated and collect within the hollow end of the member *h* around the end of tube 22^a which is heated by the spark or arc with the result that the gas will pass through 120 130

the walls of the tube 22^a into the space 20 in communication with the main bulb or X-ray tube, thus lowering the vacuum.

And the vacuum may also be raised by 5 passing current from the wire 25^a across the gap to the tube 22^a, which is surrounded by air, with resultant raising of the vacuum as hereinbefore described.

It will be understood that the structure 10 of either Fig. 5 or Fig. 6 may be used in place of the two regulators in any of the arrangements hereinbefore described and for both automatic and manual regulation.

While the structures of Figs. 5 and 6 15 above described are suited for the employment of current of sufficient tension to jump across gaps, it will be understood that the osmotic members 22^a may be heated by conduction as illustrated in Figs. 1 to 4 inclusive, or by radiation as in Fig. 7, by using 20 low tension current. Thus the conductors 25^a may be connected directly to the members 22^a without an intervening spark gap, in which case the arrangement will be the 25 same as that indicated in the previous figures. And with such connection of the members 25^a directly to the members 22^a the gas may be produced by use of higher tension current by utilizing the same structures illustrated 30 in Figs. 5 and 6 for this purpose. Or the gas may be evolved by suitably heating the gas producing material electrically as by the same current which heats the members 22^a, or by a separate current.

35 In Fig. 7 22 represents an osmotic member for use in any relation including the relations hereinbefore described. To heat the member 22 it is surrounded by the resistance coil 46, preferably spaced from the member 40 22 to allow presence of regulating gas. The coil 26 is preferably embedded in refractory non-conducting material 47. The coil 46 is connected in a circuit with any suitable source of current, as 48; and the strength 45 of the current in the circuit may be regulated by the adjustable resistance 49. To heat the member 22 the circuit is closed by closing switch 50 and the resistance 49 adjusted until the desired temperature is 50 reached, the heat transfer from the coil 46 to the member 22 being by either radiation or conduction, or both.

The tube 22 may have its closed end external to the vacuum as in Figs. 1, 2, 4, 5 55 and 6 with the heating coil 46 also external to the vacuum. Or the open end of tube 22 may be external to the vacuum and the closed end and coil 46 within the vacuum.

Where there is in the bulbs 21 a vacuum 60 regulating or other gas which would form a combustible or explosive mixture with air which might leak into the bulbs 21 because of cracking or which might otherwise be present, any suitable material may be placed 65 within the bulbs 21 to react with the un-

desired gas or gases to prevent forming a combustible or explosive mixture.

Such material is represented at Ph, Fig. 4, and may be a piece of phosphorus, preferably adhering to the wall of the bulb 21 to 70 prevent its displacement when the X-ray tube and the regulators are moved about. Phosphorus is particularly useful when hydrogen is used because it will immediately combine with the oxygen of any entering 75 air and thus prevent formation of an explosive or combustible mixture of hydrogen and oxygen.

In Fig. 8 the conductors 54 and 56 supply 80 low tension alternating current to the transformer T, R being an adjustable resistance in the circuit of the primary p whose number of turns is adjustable. The high potential secondary s delivers uni-directional high tension current through the 85 rectifying switch F, as in Fig. 3, to the positive and negative conductors P and N.

The anti-cathode A is connected to an osmotic member 22, of either a vacuum lowering or raising regulator, and to a spark gap terminal 58. The associated spark gap terminal 59 connects through conductor P to the rectifying switch F. Disposed near the tube 22 is the spark gap terminal 60, the tube 22 and terminal 60 forming a spark 95 gap whose terminals are connected in parallel with the spark gap terminals 58 and 59. Disposed near the spark gap terminals 58 and 59 is the conducting member 61 supported upon the end of the insulating member 62 carried by the armature 63 of electro-magnet 64 and pivoted at 65. A spring 66, under tension, connects at its one end to the armature 63 and at its other end to the adjusting screw 67 which adjusts the tension 100 of the spring 66. The electro-magnet 64 has its one terminal connected to the conductor 54 and its other terminal to the adjustable resistance or impedance 68 with which 105 cooperates the movable contact 69 connected by conductor 70 to the primary p, whereby the circuit of the electro-magnet 64 is in shunt to a part of the primary p. Associated with the movable contact 69 is the scale 71 reading in units corresponding with 110 different degrees of vacuum of the X-ray tube.

Assuming the osmotic tube 22 to be part 115 of a vacuum lowering regulator, and the vacuum to be too high, the fall of potential across the primary p will be high, especially if the magnetic leakage of the transformer T is low, with resultant greater current flow through the electro-magnet 64, with a given setting of the contact 69. Accordingly the electro-magnet 64 will attract its armature 63 in opposition to the spring 66 and remove the member 61 from the terminals 58 and 59, thereby producing a spark gap or increasing the length of a 120 125 130

- spark gap, with the result that the energy passed between the tube electrodes A and C will leap the gap between terminals 60 and tube 22 to heat the latter and cause a lowering of the vacuum as hereinbefore described. As the vacuum is lowered the fall of potential across the X-ray tube will diminish, as will also the fall of potential across the primary p , and accordingly the strength of current through the electro-magnet 64 will diminish and the spring 66 will withdraw the armature 63 and shorten the spark gap at 58, 59 and 61 so that the energy through the X-ray tube will no longer jump the gap between 60 and 62, but will pass from contact 59 to contact 58 through member 61, with the result that the tube 22 will cool and the vacuum will be no further lowered.
- 20 When the tube 22 is that of a vacuum lowering regulator the movement of the contact 69 toward the right, thereby cutting out some of resistance 68, will insure the automatic maintenance of a low vacuum, while movement to the left will insure automatic maintenance of a higher vacuum.

In this arrangement of Fig. 8, therefore, there is a spark gap for controlling a vacuum regulator, which spark gap is in series with the X-ray tube proper; and this regulator spark gap is shunted by another spark gap whose length is automatically varied in response to degree of vacuum of the X-ray tube.

- 35 In Fig. 9 the arrangement in the primary circuit is similar to that in Fig. 8 except that the electro-magnet now takes the form of a solenoid 72 whose core 73 is attached to the insulating lever 62 pivoted at 65 and controlled by spring 66 which is in turn adjustable by the screw 67.

The X-ray tube is here shown as provided with both a vacuum lowering regulator and a vacuum raising regulator, the former comprising the osmotic tube 22 and spark gap terminal 60 and the latter comprising the osmotic tube 28 and the spark gap terminal 74 connected through positive conductor P to one terminal of the rectifying switch F. The tube 28 is connected to the spark gap terminal 60 and to the conductor 75. The tube 22 is connected to the anode of the X-ray tube and to the conductor 76, and the spark gap terminal 74 is connected to the conductor 77. These conductors 75, 76 and 77 are disposed adjacent each other but at such distance from each other that sparking does not occur between them. Movable across and near the conductors 75, 76 and 77 is the conducting member 61 carried by the lever 62. The arrangement of the conductor 61 and the conductors 75, 76 and 77 is shown in Fig. 9^a.

Here again the solenoid 72 becomes more

strongly energized as the vacuum rises and 65 weakens as the vacuum lowers.

As the vacuum rises the lever 62 will be drawn to the left by the solenoid 72 until the member 61 passes beyond the conductor 76 and bridges only conductors 75 and 77, 70 whereupon the current is passed from the high tension switch F through the conductor P to conductor 77 to conductor 61 to conductor 75 and to spark gap terminal 60 and thence across the gap to the tube 22 and 75 thence to the X-ray tube. This heats the tube 22 with resultant lowering of the vacuum. If the vacuum becomes too low the spring 66 will draw the member 62 to the right until the member 61 passes beyond 80 the right end of conductor 77, whereupon current will pass from conductor P to spark gap terminal 74 and thence across the gap to the tube 28 and thence to conductor 75, to conductor 61, to conductor 76 and thence 85 through the X-ray tube. Accordingly the tube 28 is heated and the vacuum raised.

The setting of the contact 69 will cause the apparatus to automatically maintain a vacuum between certain upper and lower 90 limits, which limits will vary with adjustment of the contact 69.

In Fig. 10 the automatic regulation is procured in response to fluctuations in potential of the high tension circuit across the anode 95 and cathode of the X-ray tube. This method of regulation is therefore available whether or not the high tension transformer T has small magnetic leakage.

The high tension positive and negative 100 conductors P and N connect with the anode and cathode respectively as described. However, in one of these conductors, as P, there is a spark gap between the stationary terminal 78 and the adjustable terminal 79, the energy passed through the X-ray tube passing over the gap between these terminals. In this case the current for heating the regulator tubes 22 and 28 passes over the spark gaps. Connection for this purpose is made from positive conductor P to the conducting member 80 pivoted at 81 and controlled by the torsion spring 82 whose free end carries a pointer 83 which may be clamped in any desired position with respect to the scale 84, 115 similar to the scale 68 in Fig. 8, as by friction between the scale and pointer. The member 80 carries the adjustable contacts 85 and 86 coöperating respectively with the spark gap terminals 87 and 88 and normally separated therefrom by spark gaps. To the insulating member 89, attached to the beam or member 80, is attached the metallic arc 90 disposed oppositely to the stationary metallic arc 91 which latter is connected with the negative conductor N. The arcs 90 and 91 may be electrically connected to each other by the small easily flexible wire 92. On the

opposite end of the beam 80 is an adjustable counterweight 93 for balancing the beam so that its normal position shall be indicated.

In normal operation the high potential energy will leap across the gap between terminals 78 and 79 and pass through the X-ray tube to energize the same. This spark gap length is less than the sum of the lengths of the spark gaps between 86 and 88 and 88 and 28, and less than the sum of the lengths of the spark gaps between 85 and 87 and 87 and 22, with the result that normally no current will pass over these regulator spark gaps. Under normal conditions the electrostatic charges on arcs 90 and 91, being of similar sign, cause these arcs to repel each other, and this repulsive force coöperating with the counterweight 93 and the spring 82 maintain the beam 80 balanced as shown. If however the vacuum of the X-ray tube should raise, the potential across the X-ray tube terminals will increase and the potential of the arcs 90 and 91 will be higher and they will repel each other with greater force, tilting the beam 80 in a clockwise direction about its pivot 81 bringing the terminal 85 closer and closer to the conductor 87 so that eventually the spark gap at these regulator terminals is shorter than the spark gap between the terminals 78 and 79 whereupon the current will pass through the regulator spark gaps at the right heating the lowering regulator tube 22 causing the vacuum to be automatically lowered. And if the vacuum has raised to a great extent the unbalancing of the beam 80 will be so great as to bring contact 85 into engagement with contact 87, which latter then acts as a stop for the beam.

On the other hand if the vacuum of the tube is too low it will be automatically raised because of the decrease of potential of the arcs 90 and 91 allowing the beam 80 to move in a counterclockwise direction on its pivot 81 to shorten the gap at the terminal 88, thereby causing the current to pass across the spark gap between 86 and 88 to heat the raising regulator tube 28, causing the automatic raising of the vacuum. By adjusting the screw contacts 79, 85 and 86 the amount of variation of vacuum to either side of that indicated by the scale 84 may be adjusted.

If the connection 92 between the arcs 90 and 91 is omitted and when in such case the arc 90 remains as indicated in the drawing or is connected to the positive conductor P, in such latter case substantial insulation intervening between arcs 90 and 91, the arcs 90 and 91 will carry charges of opposite signs and will therefore attract each other. And this attractive force will vary with the potential difference across the X-ray tube terminals and therefore with the degree of vacuum. With falling vacuum the attrac-

tion between the arcs 90 and 91 will become less and the beam 80 will then move in a clockwise direction about its pivot 81. Accordingly for this arrangement the arcs 90 and 91 and the counterweight 93 should be interchanged as to their positions with respect to the beam 80, or the spark gaps for the regulator tubes should be interchanged.

It will be understood also that in place of osmotic regulators described in connection with Fig. 10 the ordinary gas evolving regulators may be used in association with the spark gaps described, the energy passed over these gaps serving to liberate the vacuum regulating gas.

It will be understood that while osmotic regulators have been described in connection with Figs. 8, 9 and 10, that any other type of regulator may be used, as for example, the ordinary regulators involving material which upon being heated will evolve gas within the vacuum, the spark gaps of these figures being used to pass energy to such ordinary regulators.

In Fig. 11 the osmotic tube, as 22, is shown with a thickened end 22^a which may be used as the terminal of the spark gap, such thickened end 22^a withstanding greater heat than the thinner parts or walls of the tube 22. The thickened end of the tube 22 may be produced in any suitable way, as for example, by fusing the closed end of the tube 22 until it thickens, as illustrated.

It will be understood that the osmotic members or membranes hereinbefore described may take other than the tubular forms illustrated, any form of the osmotic member or members being comprehended within our invention, except where expressly otherwise stated.

For any of the osmotic members hereinbefore described may be used any suitable alloy of osmotic material with another osmotic material or with a material which is not osmotic, or with both osmotic and non-osmotic materials.

For example, any of the osmotic members hereinbefore described may consist of an alloy of palladium and platinum, both platinum and palladium passing hydrogen, for example, by osmosis, but palladium more freely than platinum. By alloying platinum and palladium, however, there results an osmotic material which passes hydrogen with less facility than palladium alone. Such alloys may with advantage be used with different partial pressures of the regulating gas or gases and with different degrees of dilution of the regulating gas or gases.

While the air cooling of the X-ray tube hereinbefore described is of advantage, it will be understood that our invention is not limited to the use of our herein claimed

regulators in connection with an air cooled tube.

Pursuant to requirement for division, we claim in our application Serial Number 5 195,009, filed October 6, 1917, certain subject matter not herein claimed.

What we claim is:

1. Means for regulating the vacuum of a vacuum tube comprising an osmotic member forming a wall of said tube, different gases external to said tube in contact with said osmotic member, said member when heated adapted to allow passage therethrough of one or more of said gases and to 10 exclude another or others of said gases, and means for electrically heating said member including a spark gap in proximity to said member.
2. A regulator for the vacuum of a vacuum tube comprising an osmotic member, a mass of porous material charged with gas evolving material disposed in proximity to said member, and electrical connections to said member and said porous material.
3. A regulator for the vacuum of a vacuum tube comprising an osmotic member, a mass of porous material charged with gas evolving material disposed in proximity to said member, electrical connections to said member and said porous material, and a spark gap terminal spaced from said member.
4. A regulator for the vacuum of a vacuum tube comprising an osmotic member, a container for electrolyte, said container having a porous wall, electrical connection into said container, a conductor extending through said porous wall and spaced from said member.
5. A regulator for the vacuum of a vacuum tube comprising an osmotic member, a container for gas evolving material, said container having a porous wall, and a conductor extending through said container and said porous wall and spaced from said member.
6. The combination with a vacuum tube, of a regulator for raising and lowering the vacuum of said tube comprising an osmotic member forming a wall of said tube, gas evolving material, means for subjecting said material to the effects of an electric current to cause evolution of gas, means for electrically heating said osmotic member for allowing passage of the evolved gas therethrough, and means for electrically heating said member without evolution of gas for passage of gas from said vacuum tube to the exterior of said osmotic member.
7. A regulator for the vacuum of a vacuum tube comprising an osmotic member forming a wall of said tube, a portion of the exterior of said wall exposed to the atmosphere, means for supplying regulating gas

to another portion of the exterior of said member, and means for heating said member for causing passage of gas therethrough to or from the interior of said tube.

8. A regulator for the vacuum of a vacuum tube comprising an osmotic member forming a wall thereof, gas evolving material in proximity to said member, a conductor disposed in proximity to said member, and means for passing current through said conductor and said gas evolving material.

9. An osmotic member or membrane having a thin gas passing portion and an integral massive portion.

10. An osmotic member having integral thin and massive portions, and means for raising the temperature of said massive portion, whereby heat is conducted to said thin portion.

11. An osmotic member comprising integral thin and massive portions, said massive portion forming a terminal of a spark gap.

12. The combination with an X-ray tube, of a spark gap in series therewith, a vacuum regulator comprising a spark gap in parallel with said first named spark gap, and means for altering the length of one of said gaps.

13. The combination with an X-ray tube, of a spark gap in series therewith, a vacuum regulator comprising a spark gap in parallel with said first named spark gap, and means responsive to change in degree of vacuum of said X-ray tube for altering the length of one of said spark gaps.

14. The combination with an X-ray tube, of a spark gap in series therewith, a vacuum regulator comprising a spark gap in parallel with said first named spark gap, a movable member adapted to change the length of one of said spark gaps, and electro-magnetic means controlling said member.

15. The combination with an X-ray tube, of a spark gap in series therewith, a vacuum regulator comprising a spark gap in parallel with said first named spark gap, a movable member adapted to change the length of one of said spark gaps, and electro-magnetic means responsive to changes in degree of vacuum of said X-ray tube controlling said member.

16. The combination with an X-ray tube, of a spark gap in series therewith, a vacuum regulator comprising a spark gap in parallel with said first named spark gap, a movable member adapted to change the length of one of said spark gaps, a step-up transformer supplying said X-ray tube, and electro-magnetic means connected in the primary circuit of said transformer controlling said member.

17. The combination with an X-ray tube, of a spark gap in series therewith, a vacuum regulator comprising a spark gap in par-

lel with said first named spark gap, a movable member adapted to change the length of one of said spark gaps, a step-up transformer supplying said X-ray tube, and electro-magnetic means connected in parallel with the primary winding of said transformer controlling said member.

18. The combination with an X-ray tube, of a spark gap in series therewith, a vacuum 10 regulator comprising a spark gap in parallel with said first named spark gap, a movable member adapted to change the length of one of said spark gaps, a step-up transformer supplying said X-ray tube, and electro- 15 magnetic means connected in parallel with a part of the primary of said transformer controlling said member.

19. The combination with an X-ray tube, of a spark gap in series therewith, a vacuum 20 regulator having a spark gap, said spark gap connected in parallel with each other, and means for varying the length of said first named spark gap.

20. The combination with an X-ray tube, 25 of a spark gap in series therewith, a vacuum regulator having a spark gap, said spark gaps connected in parallel with each other, and means responsive to the variations in the vacuum of said X-ray tube for varying 30 the length of said first named spark gap.

21. The combination with an X-ray tube, of a spark gap in series therewith, a vacuum regulator having a spark gap, said spark gaps connected in parallel with each other, 35 and means for varying the length of said regulator spark gap.

22. The combination with an X-ray tube, of a spark gap in series therewith, a vacuum regulator having a spark gap, said spark 40 gaps connected in parallel with each other, and means responsive to the variations in the vacuum of said X-ray tube for varying the length of said regulator spark gaps.

23. The combination with an X-ray tube, 45 of vacuum raising and lowering regulators comprising spark gaps, means for shunting said spark gaps, and means responsive to changes in degree of vacuum of said X-ray tube controlling said means.

50 24. The combination with an X-ray tube, of vacuum raising and lowering regulators comprising spark gaps, means for shunting said spark gaps, and electro-magnetic means responsive to changes in degree of vacuum 55 of said X-ray tube controlling said means.

25. The combination with an X-ray tube, of vacuum raising and lowering regulators, a spark gap for each of said regulators, a spark gap in parallel with each of said 60 spark gaps, and means for varying the length of a spark gap of each pair of parallel connecting spark gaps.

26. The combination with an X-ray tube, of vacuum raising and lowering regulators,

a spark gap for each of said regulators, a 65 spark gap in series with said tube and in parallel with each of said spark gaps, and means for varying the length of a spark gap of each pair of parallel connected spark gaps. 70

27. The combination with an X-ray tube, of vacuum raising and lowering regulators, a spark gap for each of said regulators, a spark gap in parallel with each of said 75 spark gaps, and means responsive to variations in degree of vacuum of said X-ray tube for varying the length of a spark gap of each pair of parallel connected spark gaps.

28. The combination with an X-ray tube, 80 of vacuum raising and lowering regulators, a spark gap for each of said regulators, a spark gap in parallel with each of said spark gaps, and electro-magnetic means responsive to variations in degree of vacuum 85 of said X-ray tube for varying the length of a spark gap of each pair of parallel connected spark gaps.

29. The combination with a vacuum tube, 90 of a vacuum lowering and raising regulator, a scale having markings corresponding with degrees of vacuum, an index associated with said scale, means for controlling said regulator including electro-magnetic means, and means determining the operation of said 95 controlling means set with said index.

30. The combination with a vacuum tube, of a scale having markings corresponding with degrees of vacuum, an index associated 100 with said scale, a vacuum regulator, and means for controlling said regulator comprising electro-magnetic means and means set by movement of said index.

31. The combination with a vacuum tube, 105 of a vacuum regulator, a scale having markings corresponding with degrees of vacuum, an index associated with said scale, means for controlling said regulator including electro-magnetic means, and current-regulating means determining the operation of 110 said controlling means set with said index.

32. The combination with a vacuum tube, of a scale having markings corresponding with degrees of vacuum, an index associated 115 with said scale, a transformer for exciting said vacuum tube, a vacuum regulator, means in shunt with the primary of said transformer for controlling said regulator, said means comprising an electro-magnet and current-regulating means set with said 120 index.

33. The combination with a vacuum tube, 125 of a scale having markings corresponding with degrees of vacuum, an index associated with said scale, a transformer for exciting said vacuum tube, said transformer having low magnetic leakage, a vacuum regulator, means in shunt with the primary of said

transformer for controlling said regulator, said means comprising electro-magnetic means and current-regulating means, said current regulating means being set with said index.

34. The combination with a vacuum tube, of a vacuum regulator, a transformer for exciting said vacuum tube, said transformer having low magnetic leakage, means in shunt with the primary of said transformer for controlling said regulator, said means comprising electro-magnetic means and current-regulating means.

35. The combination with a vacuum tube, of a vacuum regulator comprising an osmotic member, a transformer for exciting said tube and supplying current to said regulator, said transformer having low magnetic leakage, and electro-magnetic means in electrical connection with the primary of

said transformer for controlling said regulator.

36. The combination with a vacuum tube, of a vacuum regulator comprising an osmotic member, a transformer for exciting 25 said tube and supplying current to said regulator, and electro-magnetic means in electrical connection with the primary of said transformer for controlling said regulator.

37. In a vacuum regulator, an osmotic 30 member of material containing platinum and palladium.

38. In a vacuum regulator, an osmotic member composed of an alloy of platinum and palladium. 35

In testimony whereof we have hereunto affixed our signatures this 10th day of June, 1915.

HOMER CLYDE SNOOK.
EDWIN W. KELLY.
